UNITED STATES PATENT OFFICE.

FRED H. DANIELS, OF WORCESTER, MASSACHUSETTS.

RAIL-BOND.

SPECIFICATION forming part of Letters Patent No. 596,202, dated December 28, 1897.

Application filed July 26, 1897. Serial No. 645,901. (No model.)

To all whom it may concern:

Be it known that I, FRED H. DANIELS, a citizen of the United States, residing at Worcester, in the county of Worcester and State of 5 Massachusetts, have invented certain new and useful Improvements in Rail-Bonds, of which the following is a specification.

My invention relates to rail-bonds for electric railways, and particularly to that class 10 of rail-bonds in which the terminals or ends are made integral with the body of the bond, and are of cylindrical or tubular shape, with an opening therethrough for a drift-pin or 15 taper-tool; and the object of my invention is to reduce the cost of this style of bond by decreasing the amount of copper required at the terminals or ends of the bonds without decreasing the area or surface of the terminals which are in contact with the rails or in 20 any way affecting the efficiency of the rail-bond. I have found that in manufacturing this style of rail-bond from lengths of copper rods a portion of the round rod adjoining the terminal may be put into the terminal, leaving the rod half-round or of semi-circular shape next to the terminal, thus making a considerable saving of copper in each 25 rail-bond, and consequently reducing the cost of the bond.

30 My invention consists in certain novel features of construction of my rail-bond, as will be hereinafter fully described.

Referring to the drawings, Figure 1 shows a complete rail-bond of my improved construction. Fig. 2 is a sectional view of the terminal or end, and of a rail with which it is combined. Fig. 3 is an end view of the terminal or end looking in the direction of arrow *a*, Fig. 2; and Fig. 4 shows one end of 40 a rail-bond rod with the terminal formed thereon before the rod is bent, as shown in the other figures. Figs. 2 to 4, inclusive, are shown on an enlarged scale.

In the accompanying drawings, 1 is the rail-bond, preferably made from a straight length 45 of copper rod of circular shape in cross-section. The terminals 2 are preferably made integral with the body of the bond, and are preferably formed by drop-forging.

50 In making the terminals 2 a portion of the rod adjoining the terminal is used to form

the terminal, so that the rod or bond adjoining the terminal is of half-round or semicircular shape in cross-section, as shown in Fig. 4.

After the terminal is formed, as above described, with the annular shoulder or flange 2' thereon to bear against the rail, a hole 3, preferably having a double-taper portion, is drilled through the terminal either before or after the non-circular end of the rod is bent 55 to cause the terminal 2 to extend at substantially right angles to the main body of the bond, as shown in Figs. 2 and 3.

A groove or depression 3' leading to the opening 3 through the terminal is preferably 65 made in the non-circular portion of the bond adjoining the terminal, as shown, and this depression serves as a guide to direct the drift-pin (not shown) into the opening 3 and to hold the drift-pin in place in the operation 70 of driving it into the hole in the terminal.

By using a portion of the copper rod adjoining the terminal in making the terminal I decrease the amount of copper necessary to be used in the bond without decreasing 75 the area or surface of the terminal which is in contact with the rail and without affecting the efficiency of the bond.

By providing the portion of the rod adjacent to the terminal with the longitudinal 80 groove or depression the rod is made substantially semitubular in cross-section at that point, whereby it has the greatest strength with the least amount of material, and as it is well known that the current passes upon 85 the exterior rather than through the mass it is evident that the depression also increases the carrying capacity of the rod at a point which would otherwise have the least area, owing to the reduction in the size of the rod 90 on account of taking a portion of it to form the terminal. By this construction the groove or depression performs a triple or threefold function, as it forms a guide for the drift-pin into the opening of the terminal, increases 95 the carrying capacity of that portion of the rod, and also decreases the amount of material without decreasing the strength of the rod in like proportion.

It will be understood that the details of 100 construction and form of my rail-bond may be varied, if desired. A taper-tool may be

used instead of a drift-pin, and the shape of the opening through the terminal may be varied, as desired.

Having thus described my invention, what I claim as new, and desire to secure by Letters Patent, is—

As an improved article of manufacture, a rail-bond comprising a rod, each end of which is reduced and provided with a tubular terminal, the portion of the rod adjacent to the

terminal being provided with a longitudinal recess or depression forming a semitubular portion in alinement with the tubular terminal, and an annular flange or shoulder between the tubular and semitubular portions, substantially as set forth.

FRED H. DANIELS.
